UNITED STATES PATENT OFFICE

159,927

VANITY CASE OR THE LIKE

Alfred F. Reilly, North Attleboro, Mass., assignor to Evans Case Co., a corporation of Massachusets

Application January 28, 1950, Serial No. 7,536

Term of patent 14 years

(Cl. D86—10)

To all whom it may concern:

Be it known that I, Alfred F. Reilly, a citizen of the United States of America, residing at North Attleboro, county of Bristol, State of Massachusetts, have invented a new, original, and ornamental Design for a Vanity Case or the Like, of which the following is a specification, reference being had to the accompanying drawing, forming a part thereof.

Fig. 1 is a side elevational view of a vanity case or the like showing my new design; and

Fig. 2 is an end elevational view thereof.

The dominant part of the design is shown in full lines.

I claim:

The ornamental design for a vanity case or the like, substantially as shown and described.

ALFRED F. REILLY.
